UNITED STATES PATENT OFFICE.

GEORGE EVANS WEBB, OF MILWAUKEE, WISCONSIN, ASSIGNOR TO KOEHRING COMPANY, OF MILWAUKEE, WISCONSIN, A CORPORATION.

CONCRETE-MIXER WATER-SUPPLY MEANS.

Application filed April 24, 1925. Serial No. 25,634.

This invention embodies certain improvements in water supply equipment for concrete mixing machines of the general type presented in the United States patent of 5 Lichtenberg #1,523,548, issued January 20, 1925, wherein there is utilized the principle of a positive water forcing means for introducing the water required for mixing a batch of aggregates, into the drum of the 10 mixer. In the operation of mixing machines, the time factor incident to the introduction of the aggregates and water is very material to the efficiency of the machine. With this especially in view the mechanism 15 of the present invention enables a material reduction in this time factor, in so far as it relates to the supply of a requisite quantity of water to the mixing drum for each batch of dry aggregates.

20 The primary advantages of the present improvements have reference particularly to the novel mechanism employed for positively driving the water forcing or pumping means, the controls whereby the said means is started into operation and stopped, and the utilization of driving power, preferably taken from the power means for actuating certain of the mixing machine parts, for the operation of the said pumping or 25 water forcing instrumentalities.

A full understanding of the invention will be had upon reference to the following description, and to the accompanying drawings in which similar reference characters 30 refer to similar parts, and in the latter of which the various figures are described briefly as follows:

Figure 1 is a side view of the framework 35 of a mixing machine of the side loader type, certain parts of the machine broken away and illustrating the loading skip at its down position in dotted lines and at the limit of its discharging position in full lines.

Figure 2 is an enlarged sectional view of 40 the pump operating means and certain parts of the controlling mechanism for the latter.

Figure 3 is a transverse sectional view taken through the operating gearing illustrated in Figure 2.

45 Figure 4 is a fragmentary view in section and elevation showing the control member for the ratchet mechanism of the pump driving gear, in a position permitting the ratchet pawl to be operated.

Figure 5 is a view similar to Figure 4 but 55 showing the control member positioned so that the driving pawl is inactive.

Figure 6 is a plan view with a portion of the drum broken away and shown in section, illustrating certain of the main parts shown in Figure 1.

Figure 7 is a somewhat diagrammatic view showing the three positions of the skip, the lowermost as when the skip is on the grade, the next uppermost dotted line position at which point the skip acts to initiate the operation of the pump and the topmost position at which the skip fully discharges its contents of dry aggregates into the mixer, the engaging means between the skip and 60 trip rod being shown clearly.

Figure 8 is a fragmentary view partly in section showing the driving rack of the pump system with the upper trip that contacts with the control member, and the adjustable lower trip which operates the inlet valve mechanism to close said valve at a predetermined point in the movement of the pump piston, thereby measuring the quantity of liquid or water admitted to the measuring chamber or cylinder.

Figure 9 is a sectional view showing more clearly the operating device for the inlet valve and the inlet valve structure itself.

Fig. 10 is a view of the parts shown in 85 Figure 9 largely in elevation, and taken at a right angle to the view of Figure 9.

Figure 11 is a top plan view showing a modification of the invention wherein the drive for the water supply mechanism is 90 taken off of the mixing drum and used also for operating a fan for cooling the water from the cooling water jacket of the motor.

Figure 12 is a view in side elevation, partly broken away, of the parts shown in 95 Figure 11.

Figure 13 is a fragmentary view in end elevation bringing out clearly the connection between the drum operating shaft and the fan operating shaft.

100 Those versed in the art to which this invention appertains are familiar with concrete mixer construction so that the parts of the mixing machine having to do primarily with the present improvements may be very 105 briefly referred to as the mixing drum 1, the base or truck frame 2 on which it is supported, the skip 3 by which the drum 1 is

charged with dry aggregates, the super-structure or framework 4 which carries the skip hoist shaft 5 on which are supported cable drums 6 that lead over sheaves 7 and 5 connect with the skip 3 for elevating the same as usual. The drum 1 is equipped with the charging chute 8 at the under side of which is disposed the water supply passage 9, having the egress opening 10, by which 10 water is directly admitted into the drum 1 against the inner side of the adjacent head thereof. The chute 8 coacts with the charging skip 3 in the customary way, and the water passage and egress opening 10 receive 15 the water with which the drum 1 is to be charged, on introducing each batch of dry aggregates, from a water pipe 11 which communicates with the lower end of the cylinder 12.

20 The cylinder 12 constitutes the measuring water chamber of the invention and is equipped with a discharge valve 13 at its lower discharge end, which valve is loaded so as to resist opening movement, by weight 25 means 14 sufficient to maintain the water supplied to the chamber 12 against outflow therefrom until a positive force is exerted to discharge or eject such water.

I provide a positive operating mechanism 30 for discharging the measured contents of the chamber or cylinder 12, somewhat similar to the means set forth in the Letters Patent, previously referred to herein. Said discharging means includes a piston 15 in 35 the chamber 12 which piston is equipped with a piston rod actuator in the form of a driving rack 16, that extends through an opening in the upper head 17 of the cylinder 12. The head 17 is provided with a casing 18, in which are mounted certain gears and 40 ratchet mechanism by which the piston 15 may be positively driven in order to discharge the contents or water within the chamber 12.

45 The positive driving means for the piston 15 comprises a shaft 19 mounted on the framework 4 in suitable bearings and connected at its upper end by bevel gears 20 and 21 with the skip hoist shaft 5. This 50 shaft 5 is operated as customary in machines of this type, Letters Patent #1,107,171 to Koehring, issued August 11, 1914, showing a conventional operating means such as may be used and intended to be illustrated in a 55 general way by Figure 1.

In order to meet with the present day requirements of an efficient water charging apparatus for concrete mixers, the water must be introduced into the mixing drum 60 during that cycle of action which takes place after the skip 3 starts upward to its discharging position and reaches the final upward limit of its movement. It is for this reason that the power for operating the 65 water supply means of the invention may be

taken off of the shaft 5, which of course is in active operation whilst the skip hoisting movement occurs.

From the shaft 19 motion is transmitted at the lower end of the shaft to bevel gears 70 22 on shaft 19 and bevel gear 23 on a horizontal shaft 24 mounted within the casing 18 on the cylinder 12. Integral with the bevel gear 23 or suitably secured to the shaft 24 is an arm 25 that carries a pin 26 75 on which is mounted the pawl 27 seen best in Figures 4 and 5, having the tail 28. The pawl 27 is adapted to cooperate under suitable control with a single tooth ratchet wheel 29 on shaft 24 and preferably cast 80 integral with the driving gear or pinion 30, loosely mounted on the shaft 24 and having its teeth engaging the rack teeth 16^a of the driving rack bar which is attached to the piston 15.

85 The ratchet pawl 27 is constantly urged toward a position in which it will engage at its nose with the tooth of the ratchet wheel 29 by means of a spring 27'.

Certain means are provided in the form 90 of the control member 31 consisting of a rectangular plate sliding vertically in the casing 18, to cooperate with the tail 28 of the pawl 27 to prevent said pawl from engaging the tooth of the ratchet wheel 29 except when it is desired to drive the gear 30 to positively driving the rack bar 16 downwards. The cooperation of the control member 31 is best seen in Figures 4 and 5. In 95 Figure 5 the position of the control member 31 is such that the tail 28 of the pawl 27 operates on the surface 31' of the control member and the pawl is thus held tilted in an inoperative position in relation to the ratchet 29 so that it cannot communicate 100 movement to the member 29 which would actuate the rack driving gear 30. In the position of the parts in Figure 4 the control member 31 has been raised until a recess 105 31'' is opposite the tail of the pawl 27 and permits the spring 27' to shift the pawl into engagement with the wheel 29.

110 The means for operating the control member 31 is automatic and includes a lever 32 having a pin and slot connection 33 with member 31, said lever being pivoted at 34 on a bracket carried by the casing 18. The other end of the lever 32 is equipped with a rod and spring device, the rod 35 and the spring 36, adapted to be operated by the 115 skip 3 in the manner shown in Figure 7. In other words the lower end of the rod 35 has a foot piece 35' projecting therefrom, with which foot piece a trip arm 3^a on the skip bracket 3^b is adapted to coact. As the 120 skip is raised in a manner to be later described, the rod 35 is pulled downwards to elevate the control member 31.

125 At the lower end of the cylinder or water chamber 12 is mounted the water supply 130

valve 37 in a valve casing 38. This valve 37 is connected with a rod 37^a leading upwards from the valve to a lever 37^b seen best in Figure 8, and not seen in Figure 1 because it is behind the cylinder 12 and casing 18. On the driving rack 16 there is carried an adjustable trip block 16^a, see Figure 8, adapted during upward movement of the rack to engage the lever 37^b and rock the latter so that the rod 37^a will close the valve 37 and discontinue the supply of water entering the chamber 12.

15 There is also carried at the upper end of the driving rack 16, a trip block 16^b which functions to engage a lug 31^a at the upper end of the control member 31, to force said control member downwards as the piston 15 reaches its lower limit of movement in discharging the contents of the chamber or 20 cylinder 12.

The operating connections between the rod 37^a and the water inlet valve 37 by which the cylinder 12 is charged by a measured quantity of water are peculiar and are shown best in Figures 9 and 10. In these figures it will be seen that some distance above the valve casing 38 is a shaft 39 having an arm 40 connected with the rod 37^a and a second arm 41 connected with the end lever 42 which is also adapted to operate the valve 37 manually, as later set forth. The arm 41 is attached pivotally and slidably to the lever 42 and said lever is connected to a knocker arm 43 by the pivot 44 also operating in a slot in the lever. The knocker arm 43 is equipped with a double hammer head 45 capable of impinging the opposite ends of a valve actuating lever 46, the parts 43 and 46 having a common axis on a bracket projecting from the casing 38.

With the parts as thus far described, presenting the preferred form of my invention, the operation of the whole mechanism is as follows:

1812
45 It will be assumed that the loading skip 3 is on the grade or at its lower limit of movement. The operator grasps the lever 42 and moves it downwards, see Figure 9, placing the springs 48 under increased tension and 50 rocking the knocker arm 43 to the left. As soon as the pivot 44 passes over the center 47, the movement of the arm 43 is greatly accelerated to drive the hammer head 45 with considerable velocity, against the left head 55 of the lever 46. The valve 37 is operated in this way and water begins to pass immediately into the chamber 12. The entrance of the water into the chamber 12 under pressure raises the piston 15 and correspondingly raises the driving rack bar 16 thereof. 60 At a certain point of the upward movement of the piston 15, dependent upon the adjustment of the trip block 16^a of Figure 8, said block 16^a actuates the lever 37^b, the rod 37^a, 65 and the valve connecting parts shown in

Figure 9 to elevate the lever 42 and cause a movement of the hammer head 45 in the direction opposite that previously referred to. The result is the closing of the valve 37 and stoppage of upward movement of the piston 15, which stoppage determines the quantity of water received in the chamber 12. By adjustment of block 16^a according to graduations that may be placed on the rack bar 16, see Figure 8, the amount of water received in the chamber 12 may be exactly determined. As this amount of water is always the same for a mixer of predetermined size, once the block 16^a is adjusted it need not be again adjusted in the use of the mixing machine, except for varying conditions of aggregate.

We have now supplied the chamber 12 with a predetermined quantity of water to be later forced into the mixer when the latter is charged or being charged with dry aggregates. In the upward movement of the rack bar 16, as soon as the control member 31, is in the position of Figure 5, the pawl 27 becomes inactive and the gear 30 freely rotated counterclockwise under the actuation of the rack bar. 85 90

The operator of the machine now raises the skip 3 in the usual way, with its charge of dry aggregates. When the skip reaches the position illustrated in the lower dotted lines of Figure 7, or approximately 20° above the horizontal, the foot piece 35^a of the rod 35 will have been depressed sufficiently to pull down on the lever 32 and raise the control member 31 from its position Figure 5 for adjustment of the parts to its position of Figure 4 adjustment. This action shows the pawl 27 impelling its spring 27' to force it into engagement with the ratchet wheel 29, whereupon the gear 30 under the influence of the ratchet wheel actuation will immediately turn under power of the driving gear 22 and shaft 19, and in a clockwise direction. The gear 30 thus forces the driving rack 16 downwards with its piston 15 and the force thus generated causes the loaded discharge valve 13 at the bottom of the chamber 12 to be opened and the water in the chamber 12 is discharged under pressure through the pipe 11 and passage 9 into the mixing drum 1. When the water in the chamber 12 is fully expelled therefrom and received in the drum 1, the skip 3 will have reached its highest elevation and fully discharge its contents of dry aggregates into the drum. Furthermore at this time, the piston 15 will have reached the bottom of the cylinder 12 and the automatic acting trip block 16^b will have struck the lug 31^a of control member 31, shifting said control member back downwards to its position of Figure 5 at which time the surface 31' of the control member 31 will re-engage the tail 28 of the pawl 27 disconnecting the pawl from the ratchet wheel 29 and discontinuing

the downward rack drive of the piston 15 and its rack bar 16.

The control member 31 which slides up and down is acted on by a roller 50 pushed against the same by a coil spring 51, see Figure 2 for this feature. The roller 50 is adapted to engage in notches 52, the ends of which notches are beveled to cause continued movement of the control member when the roller reaches the slope or bevel of the notches, making certain that the control member is positively accurate as regards the measuring control operation of the said member 31. The location of the recess 31" in the control member 31 must likewise be carefully determined as it predetermines the power for discharged stroke of the piston in the chamber 12.

In Figures 12 and 13 the power shaft 5^a for operating the drive rack 16 is geared to the drum 1 as shown at 54 and has worm gear connection 55 with the shaft 24^a that corresponds with the shaft 24 of the first described form of the invention. In this now described construction, the shaft 5^a, carries a belt wheel 56 connected by a belt wheel 57 with another belt wheel 58 on the fan shaft 59, and the shaft 59 has the exhaust fan 60 adapted to supply a current of air useful for cooling the jacket water from the motor by which the mixing plate and other parts of the invention are driven.

Having thus described my invention, what I claim as new and desire to secure by Letters Patent, is:

1. In combination, a mixing machine and its operating mechanism, a water supply chamber having water inlet means, means establishing communication between said

40 chamber and the mixing machine for passage of water to the latter, means for charging the mixing machine with aggregates, operating mechanism independent of the charging means actuated by the operating means of

45 the mixing machine for forcing the water from the water chamber to a point of admixture with the aggregates supplied to the machine by the charging means, and means controlling said operating means from the skip.

50 2. In combination, a mixing drum and its operating means, a water chamber connected with said drum, a charging device for loading aggregates into the drum, means for positively expelling water from the water chamber and forcing it under pressure into the mixing machine, including a drive, and instrumentalities intermediate the last mentioned

55 means and the charging device for initiating the operation of the former to place the driver in action at a predetermined point in the movement of the charging device.

60 3. In combination, a mixing drum and its operating means, a water chamber connected with said drum, a charging device for load-

ing aggregates into the drum, means for positively expelling water from the water chamber and forcing it under pressure into the mixing machine, and instrumentalities intermediate the last mentioned means and the charging device for initiating the operation of the former at a predetermined point in the movement of the charging device, valve means normally cutting off communication between the water chamber and the mixing drum and automatically operable by the water under the action of the water expelling means associated with said chamber.

4. In combination, a mixing drum, a water chamber, a water flow pipe connecting the said chamber with the interior of the drum, a charging chute for the drum located above the point where said pipe enters the drum, and means for forcibly expelling the water from the water chamber and causing it to pass under pressure into the drum through said pipe.

5. In combination, a mixer, operating means, a water chamber, an aggregate charging device associated with the mixer to supply aggregated materials thereto, means for forcing the water in water chamber therefrom into the mixer, a drive mechanism for said forcing means, means for operatively connecting said drive mechanism with said forcing means, and means included in the forcing means for discontinuing the operative connection between the drive means and the said forcing means.

6. In combination, a mixer, drive mechanism therefor, a pump comprising a water chamber and piston in said chamber, a driving bar connected with said piston to move it to expel water from the chamber, means for supplying water expelled from the chamber to the mixer, means for connecting the drive mechanism with said driving bar, and means on said driving bar for disconnecting the drive mechanism from said bar at a predetermined time.

7. In combination, a mixer, a water pump connected with the mixer to supply water thereto, an inlet for said pump for admitting water thereto, means for operating the pump, normally disconnected therefrom and adapted to be connected therewith at will, and means operated by said pump for disconnecting it from its operating means, together with means operated by said pump the cutting off the supply of water at the inlet at a certain time in the pump action.

8. In combination, a mixer, a pump for forcing water into the mixer having an inlet by which water is supplied to the pump, a valve for said inlet, the pump comprising a piston adapted to be moved by the water from the inlet as said water fills the pump, operating means for said piston, and means controlled by movement of the piston to disconnect it from said operating means.

9. In combination, a mixer, a pump for forcing water into the mixer having an inlet by which water is supplied to the pump, a valve for said inlet, the pump comprising a piston adapted to be moved by the water from the inlet as said water fills the pump, operating means for said piston, and means controlled by movement of the piston to disconnect it from said operating means, and other means operated from the piston for closing said inlet valve to cut off flow of water to the pump from the inlet. 70
10. In combination, a mixer, a pump for forcing water into the mixer having an inlet by which water is supplied to the pump, a valve for said inlet, the pump comprising a piston adapted to be moved by the water from the inlet as said water fills the pump, operating means for said piston, and means controlled by movement of the piston to disconnect it from said operating means, and other means operated from the piston for closing said inlet valve to cut off flow of water to the pump from the inlet, and a charging device for the mixer cooperating to operatively connect the piston with the operating means therefor. 75
11. In combination, a mixer, a pump for forcing water into the mixer comprising a piston, a driving bar for the piston, operating mechanism for actuating said driving bar normally disconnected therefrom, an inlet valve controlling flow of water into the pump, a device for charging aggregates into the mixer, means operative by said charging device for connecting the driving bar with said operating means, to cause the pump to force the water therefrom into the mixer, and means operated by said driving bar for closing said inlet valve to discontinue the flow of water into the pump. 80
12. In combination, a mixer, a pump, comprising a piston, and piston chamber having water inlet, an inlet valve governing said inlet, a connection between said piston chamber and the mixer through which water may be forced into the latter, operating mechanism, a driving bar connected with the piston for moving the latter, a charging skip for the mixer, means normally inoperative adapted to connect the driving bar with said operating means and comprising a control member, means for operating said control member from the charging skip to automatically connect the operating means with the driving bar, means carried by the driving bar to actuate said control member to disconnect the driving bar from its operating means. 85
13. In combination, a mixer, a pump, comprising a piston, and piston chamber having water inlet, an inlet valve governing said inlet, a connection between said piston chamber and the mixer through which water may be forced into the latter, operating mecha- 90
- nism, a driving bar connected with the piston for moving the latter, a charging skip for the mixer, means normally inoperative adapted to connect the driving bar with said operating means and comprising a control member, means for operating said control member from the charging skip to automatically connect the operating means with the driving bar, means carried by the driving bar to actuate said control member to disconnect the driving bar from its operating means, the operating means for closing the inlet valve controlled by said control member, and adapted to be initiated into action by the driving bar. 95
14. In combination, a concrete mixer and operating means therefor, water supply means for the mixer, comprising a water chamber, skip actuating means operated by said operating means, and means for forcibly moving the water from the water chamber to the mixer operated independently of said skip actuating means. 100
15. In combination, a concrete mixer, water chamber therefor, communicating with said mixer, a skip, means for raising and lowering the skip, operating means for the mixer, means for moving the water forcibly from the water chamber to the mixer, and means operated by the mixer for operating the last mentioned means. 105
16. In combination, a concrete mixer, water chamber therefor, communicating with said mixer, a skip, means for raising and lowering the skip, operating means for the mixer, means for moving the water forcibly from the water chamber to the mixer, and means operated by the mixer for operating the last mentioned means, and a water cooling fan operated by the means which operates the means for moving the water from the chamber to the mixer. 110
17. In combination, a mixer, water supply means for the mixer, actuating means for forcing the water from the supply means to the mixer, means for operating said last actuating means from the mixer, and a water cooling fan also operated by said actuating means. 115
18. In combination, a mixing machine and its operating mechanism, a water supply chamber having water inlet means, means for conducting water from the said chamber to the mixing machine, a loading skip for charging the mixing machine with aggregates, means for operating the loading skip, control means intermediate the skip and the water supply chamber for causing the water to pass from said chamber to the mixing machine as the loading skip moves to a position for charging aggregates into the mixing machine, said controlling means being such that it initiates the movement of the water from the water chamber to the mixing machine shortly after the loading 120
19. In combination, a mixer, a pump, comprising a piston, and piston chamber having water inlet, an inlet valve governing said inlet, a connection between said piston chamber and the mixer through which water may be forced into the latter, operating mecha- 125
- nism, a driving bar connected with the piston for moving the latter, a charging skip for the mixer, means normally inoperative adapted to connect the driving bar with said operating means and comprising a control member, means for operating said control member from the charging skip to automatically connect the operating means with the driving bar, means carried by the driving bar to actuate said control member to disconnect the driving bar from its operating means, the operating means for closing the inlet valve controlled by said control member, and adapted to be initiated into action by the driving bar. 130

- skip starts upward in its charging movement, and maintains the flow of the water into the mixing machine during the subsequent movement of the skip as aforesaid.
19. In combination, a mixing machine and its operating mechanism, a water supply chamber, means for conducting water from said supply chamber to the mixing machine for admixture with solid aggregates charged into the latter, a loading skip for charging solid aggregates into the mixing machine, controlling means for controlling the passage of the water from the water supply chamber to the mixing machine, and connecting means between the loading skip and said controlling means whereby the water is caused to start its movement from the water supply chamber into the mixing machine at the beginning of the solid aggregate charging movement of the loading skip and maintained continuously flowing into the mixing machine during the subsequent movement of the loading skip.
20. In combination, a mixing machine and its operating mechanism, a water supply chamber, means for conducting water from said supply chamber to the mixing machine for admixture with solid aggregates charged into the latter, a loading skip for charging solid aggregates into the mixing machine, controlling means for controlling the passage of the water from the water supply chamber to the mixing machine, and connecting means between the loading skip and said controlling means whereby the water is caused to start its movement from the water supply chamber into the mixing machine at the beginning of the solid aggregate charging movement of the loading skip and maintained continuously flowing into the mixing machine during the subsequent movement of the loading skip, the said controlling means comprising a driving mechanism operated by the operating mechanism of the mixing machine and adapted to be operatively connected with the controlling means for causing movement of the water to the mixing machine, as an incident to the upward movement of the skip.
21. In combination, a mixing drum, a water chamber, a water flow pipe connecting the said chamber with the interior of the drum, the said drum comprising a head having an inlet opening through which the water and solid aggregates are charged thereinto, and the said water flow pipe being so arranged as to enter the drum and having its discharge end directed toward the inner side of the said drum head whereby the water will be caused to flow against said head as it enters the drum.
22. In combination, a mixing drum, a water chamber, a water flow pipe connecting the said chamber with the interior of the drum, the said drum comprising a head having an inlet opening through which the water and solid aggregates are charged thereinto, and the said water flow pipe being so arranged as to enter the drum and having its discharge end directed toward the inner side of the said drum head whereby the water will be caused to flow against said head as it enters the drum.
23. In combination, a mixing drum, a water chamber, a water flow pipe connecting the said chamber with the interior of the drum, and a combined charging chute for the drum and water flow pipe section, the latter forming a part of the water flow pipe previously referred to.
24. In combination, a mixing machine, a water chamber, a water flow pipe leading from said chamber to the mixing machine, a driving mechanism associated with the mixing machine, means for positively forcing the water from the chamber to the mixing machine, and a loading skip arranged to operatively connect the driving mechanism aforesaid with the said water forcing means.
25. In combination, a mixing machine, a water chamber, a water flow pipe leading from said chamber to the mixing machine, a driving mechanism associated with the mixing machine, means for positively forcing the water from the chamber to the mixing machine, and a loading skip arranged to operatively connect the driving mechanism aforesaid with the said water forcing means, said water forcing means comprising an instrumentality for disconnecting it from the driving mechanism at a predetermined time.
26. In combination, a mixing machine, a water chamber, a water flow pipe leading from said chamber to the mixing machine, a driving mechanism associated with the mixing machine, means for positively forcing the water from the chamber to the mixing machine, and a loading skip arranged to operatively connect the driving mechanism aforesaid with the said water forcing means, said water forcing means comprising an instrumentality for disconnecting it from the driving mechanism at a predetermined time, a water inlet connected with the said chamber, an inlet valve controlling said inlet, and an instrumentality operated by the water forcing means incident to the entering action of the water into the chamber closing the water inlet valve and thereby controlling the amount of water that will be received in the water chamber for subsequent passage to the mixing machine.
27. In combination, a concrete mixer, a water chamber associated therewith, a wa-

ter outlet flow pipe connecting the mixing machine and chamber aforesaid, a water inlet pipe connected with the chamber, valve means controlling the flow of water from the inlet pipe to the chamber, a piston for forcing the water from the chamber to the water outflow pipe to the mixer and means controlled from said piston for cutting off the supply of the water from the chamber

10 to the inlet pipe aforesaid.

28. In combination, a concrete mixer, a water chamber associated therewith, a water outlet flow pipe connecting the mixing machine and chamber aforesaid, a water inlet pipe connected with the chamber, valve means controlling the flow of water from the inlet pipe to the chamber, a piston for forcing the water from the chamber to the water outflow pipe to the mixer and means controlled from said piston for cutting off the supply of the water from the chamber

15 to the inlet pipe aforesaid, and including a valve, a device for operating the valve and means on the piston for actuating the said

device when a predetermined quantity of 25 water has been admitted to the chamber.

29. Means substantially as claimed in claim 28 wherein the means on the piston is movable to adjust its position to vary the quantity of water which will be received in 30 the chamber.

30. In combination, a concrete mixer, a water tank therefor, and an outflow pipe leading from said tank to the mixer, a water inlet for the tank, a piston in the tank 35 for forcing the water from the tank through the outflow pipe, operating mechanism for said piston including a driving bar, means on the driving bar for automatically discontinuing the movement of the piston 40 which forces water through the tank on the outflow pipe, and means on the said driving bar for automatically cutting off the supply of water through the tank through the inlet aforesaid at a predetermined point in 45 the movement of the piston.

In testimony whereof I affix my signature.

GEORGE EVANS WEBB.
